No. 140

Rouland A. Robbins,
design for stone patterns
Patented Aug. 7, 1847.

Des. 140

Rowland A Robbins, Baltimore, Maryland.
Letters Patent (Design No. 140) dated 7th August 1847

The schedule referred to in these Letters Patent and making
part of the same.

To all to whom these presents shall come: Be it known that I, Rowland A Robbins of Baltimore City and County of State of Maryland, have invented or produced a new design for stone, and that the following is a full, clear, and exact description thereof, reference being had to the accompanying drawing which is an isometrical view of the stone:

The sides and ends of this stone are ornamented with gothic arches, two of which are formed in the sides and one on the end; there are two dies between the arches in which there is a foliated ornament, and the lancet shaped arches rest on dies instead of columns. Within the arches there is a diamond tracery in imitation of windows, and above them are lance leaved ornaments, the whole is surmounted by a moulding. The top plate rises from the edges all around in an ogee form, the centre being indented and having a quatrefoil in bold relief within it; pendant gothic tracery hangs over the ogee curve at the sides, and the ends are furnished with shell like figures surrounded by tracery and foliated scroll work. The hearth is made projecting all around and has a sunken hearth in it; the corners are square and ornamented with leaves, the edge between the corners is indented.

I claim the above described and illustrated design for
stone patterns.
